UNITED STATES PATENT OFFICE.

WINFIELD S. MCKENZIE, OF KEMP, TEXAS.

COMBINATION-WRENCH.

SPECIFICATION forming part of Letters Patent No. 331,520, dated December 1, 1885.

Application filed August 31, 1885. Serial No. 175,751. (No model.)

To all whom it may concern:

Be it known that I, WINFIELD S. MCKENZIE, a citizen of the United States, residing at Kemp, in the county of Kaufman and State of Texas, have invented certain new and useful Improvements in Combination-Wrenches; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

- 15 This invention relates to combination-wrenches; and it consists in the combination, with the frame of an ordinary sliding-jaw wrench, of other useful tools and implements, as hereinafter fully described and claimed.
- 20 This invention further consists in the detailed construction of the separate implements forming the combination-tool, so that they can be brought into combination in the form of a single tool, which is very handy, cheap of construction, and peculiarly adapted to the wants of farmers and agriculturists.

In the drawings, Figure 1 is a side view of all the parts of a combination-tool, one of which is detached. Fig. 2 is a side view of 30 the same, but with the plow-paddle removed, and showing the other side of the tool. Fig. 3 is a side view of the paddle removed from the other portions of the tool. Fig. 4 is a cross-section through the socket of the plow-paddle.

35 Similar letters of reference indicate corresponding parts in all the figures.

A is a sliding-jaw monkey-wrench operated by means of the screw *a*, having a handle, B, for turning it, which handle is made hollow and is provided with a screw top, *b*, so that it can be used as a tallow-box. The upper portion of the wrench A forms a hammer, C, and is provided with a fixed jaw, *d*, which, in combination with a second jaw, forms the pinchers D, the said second jaw being pivoted to the body of the wrench by means of the rivet *d*.

E is a nail-claw formed in the lower end of the movable arm of the pinchers.

50 F is a useful device, pointed at one end and hooked at the other, which can also be attached to the wrench for use when required to take a stone out of a horse's shoe or probe round it to discover the whereabouts of any for-

55 eign matter which may be lodged in the hoof. This device F is provided with a projection, *f*, which engages with a slot, *a'*, in the wrench, and is secured therein by the movable arm of the pinchers. A catch, *a''*, is situated in the lower part of the wrench for holding the movable arm of the pinchers in its closed position.

60 G is a plow-paddle provided with a dovetailed projection, *g*, which fits into a corresponding dovetailed socket, *a³*, in the body of the wrench, and is adapted to be held securely 65 therein by the movable arm of the pinchers when in its closed position.

H is a screw-driver situated on the lower part of the wrench. The standard from which this screw-driver projects has a slot in it, 70 through which a bar passes and keeps the screw of the wrench in position, the stem of the said screw being provided with a circular groove, through one side of which the said bar passes.

75 Having thus described my invention, what I claim as new, and desire to secure by Letters Patent, is—

1. The combination of a sliding-jaw wrench, a tallow-box formed in the handle of the said wrench, a hammer formed integral with the said wrench, the pinchers, one jaw of which is also formed integral with the wrench, a nail-claw formed in the end of the moving handle of the pinchers, the horseshoe-pick F, a plow-paddle, and a screw-driver formed on the lower part of the said wrench, substantially as and for the purpose set forth.

2. The combination of the sliding-jaw wrench A, having the dovetailed socket *a³*, 90 the pinchers D, having a movable arm, and the plow-paddle provided with the dovetailed projection *g*, substantially as described and shown, and for the purpose set forth.

3. The combination, with the sliding-jaw wrench A, having the dovetailed socket *a³*, 95 the slot *a'*, and the catch *a''*, of the pinchers D, having a movable arm, the plow-paddle provided with the dovetailed projection *g*, and the horseshoe-pick F, having the projection *f*, 100 substantially as described and shown, and for the purpose set forth.

In testimony whereof I affix my signature in presence of two witnesses.

WINFIELD S. MCKENZIE.
